INVENTOR

Frank McChuitock.

UNITED STATES PATENT OFFICE.

FRANK McCLINTOCK, OF MOUNT VERNON, NEW YORK, ASSIGNOR TO MERGENTHALER LINOTYPE COMPANY, OF NEW YORK, N. Y., A CORPORATION OF NEW YORK.

TYPE-DISTRIBUTING MACHINE.

No. 836,832.

Specification of Letters Patent.

Patented Nov. 20, 1906.

Application filed July 1, 1905. Renewed September 18, 1906. Serial No. 335,150.

To all whom it may concern:

Be it known that I, FRANK McCLINTOCK, a citizen of the United States, and a resident of Mount Vernon, in the county of Westchester and State of New York, have invented 5 certain new and useful Improvements in Type-Distributing Machines, of which the following is a specification.

My invention relates to improvements in 10 type-distributing machines of the class wherein the types are placed one by one in individual carriers which are caused to move step by step in front of a series of type selecting and ejecting devices, all of which are caused to operate simultaneously, whereby the proper 15 types are automatically ejected from the type-carriers during the time they remain stationary. The types for distribution in machines of this character are all provided 20 with shallow nicks cut in the front edge of the type-body, the relative location of these nicks being different for each letter or character of the font.

The improvements herein shown are particularly adapted to the rotary type-distributing machines heretofore invented by me, for which I filed an application for a patent in the United States Patent Office October 17, 1902, Serial No. 127,626, and is also 25 adapted in general to any machine of this 30 general character having duplicate sets of the type selecting and ejecting devices—as, for instance, that shown in United States Patent No. 567,252, issued September 8, 1896, 35 to R. J. Moxley.

The objects of my invention are, first, to provide means whereby a page or column of type when composed of two different fonts, such as Roman and italic, may be distributed 40 at one operation, the Roman types being properly distributed into one set of cases and the italic types into the other set of cases, and, second, to provide improved means whereby the type-ejecting levers may be automatically 45 restored to their initial operative positions whenever required.

I attain these objects by means of the mechanism shown in the accompanying sheet of drawings, in which—

50 Figure 1 is a side view of one of the type-carriers and the feeler-slide, which is adapted to select and eject types having only the normal nicks. Fig. 2 is a similar view show-

ing the corresponding feeler-slide as adapted to select and eject the italic or other font of type. Fig. 3 is a sectional view on the line A A of Fig. 2. Fig. 4 is a view showing the manner in which the type-bodies are nicked. 55 Similar reference characters refer to similar parts in each of the views. 60

The two machines above referred to have the essential operative parts in duplicate, being practically a combination of two complete type-distributing machines in one structure, so that two separate pages of type may 65 be placed on the two type-galleys and the operation of distribution of the two pages proceed simultaneously, all of the type from each galley being distributed only into the set of cases contiguous thereto. 70

It frequently occurs that a page of type is composed of two or more different fonts of type—such, for instance, as Roman and italic—alternating. Heretofore in machines of this character all of the types of the second 75 or italic font which were contained in the page were made to pass through the machine without distribution, being simply transferred to a suitable receptacle or receptacles in the same order as they had appeared in the page 80 of type to be subsequently distributed by hand.

My invention consists, essentially, in providing on all of the types composing the italic or other extra font a single extra or 85 font nick in addition to the usual nicks which distinguish the several characters and making all of the trip-pins, comprising one set of the type-selecting devices, too large to enter this font-nick. 90

The drawings show my improvements adapted to the type-distributing machine formerly invented by me, which is fully shown and described in the pending application first above referred to. 95

1 is the bed-plate of the machine.

2 is the circular base to which the type-carriers 3 are rigidly secured. This circular set of type-carriers is caused by suitable mechanism to rotate around its vertical axis with 100 a step-by-step movement, each step being exactly equal to the width of a single carrier.

18 represents feeler-slides, which are equal 105 in number to the different type characters to be distributed and are fitted to move longitudinally in radially-arranged bearings 4.

- The feeler-slides are all caused to move outward simultaneously by the lever 5, the return movement being effected by the spring 6 upon the return movement of the levers.
- 5 7 is the feeler-block, which is secured to the outer end of the feeler-slide 18 and to which the type-selecting nick-pins 8 are secured. The relative location of these nick-pins is different for each feeler-block in each 10 complete set and correspond in number and location with the number and location of the shallow nicks which are cut in the edge of the several letters or characters in the font of type.
- 15 9 is the tripping-pin, which passes through a bearing in the upper part of the feeler-block 7 and has a small stop 10 secured thereto.
- 20 11 is the tripping-hook, which is pivoted to the feeler-block at the point 12. This tripping-hook is normally held forward in the position shown in Fig. 1 by means of the spring 13, in which position the tripping-pin is forced inward and held with its end exactly 25 in line vertically with the ends of the nick-pins 8.
- 14 is the type-ejecting lever, which is pivoted to the feeler-slide 18 at the point 15. The outer end of the type-ejecting lever is 30 normally supported on the inner edge of the tripping-hook 11, in which position the ejector-lug 16 is held too high to engage the top of the type-ejector 17 during the outward movement of the feeler-slide. The types 35 are placed singly in the carriers with the nicks outward by the usual automatic devices which separates them one by one from the page on the galley, and each type is securely retained in the carrier by means of the 40 type-clamp 19.
- The two feeler-slides shown being the corresponding ones from each of the two sets in the machine are identical in every respect except that the end of the tripping-pin in Fig. 45 2 is larger than that in Fig. 1. Their nick-pins 8 are so located as to register with the usual nicks of the type *a*. (Shown in Fig. 4.) When it is desired to use the machine for distributing a page composed of two fonts of 50 type, such as Roman and italic, only one of the two type-galleys will be used, which will be the one adjacent to the set of feeler-slides having the small tripping-pins, as shown in Fig. 1.
- 55 The action of each of the feeler-slides shown when caused to operate upon the italic "*a*" type will first be considered.
- Referring first to Fig. 1, it will be seen that the feeler-slide has been moved inward its 60 full distance, which allows the nick-pins 8 and also the tripping-pin to enter, respectively, the two distinctive type-nicks and the upper font-nick. The tripping-pin is thus not forced outward, as would evidently be the 65 case if the Roman "*a*" type were substituted,

and consequently the type-ejecting lever 14 is retained in its normal position, so that the type is not ejected from the carrier during the ensuing outward movement of the feeler-slide. When the carrier in its step-by-step 70 movement reaches the second "*a*" feeler-slide, (shown in Fig. 2,) the nick-pins 8 again register with and enter the two distinctive type-nicks. The enlarged end of the tripping-pin 9 being unable, however, to enter the font-nick is forced outward, whereby the tripping-hook 11 is moved out to a sufficient distance to allow the front end of the type-ejecting lever 14 to drop to the position shown. When the feeler-slide 18 is now 80 caused to make its return outward movement, the ejector-lug 16 will engage with the top of the type-ejector 17 and move it outward until the type is free from the type-clamp 19, when it immediately drops down 85 into the open end of the tube 20, which guides it to its proper channel in the type-case in the usual manner.

Since the Roman "*a*" type having no font-nick will thus be selected and ejected by 90 either of the feeler-slides, it is evident that when Roman type only is to be distributed a page may be placed upon each galley and the machine be operated as a double machine, exactly as shown and described in the prior 95 application, Serial No. 127,626.

It is necessary after any type-ejecting lever 14 has been allowed to drop to the operative position (shown in Fig. 2) that it be returned at once to its initial position. (Shown 100 in Fig. 1.) The present invention provides means whereby this operation is effected without the use of the special mechanical devices heretofore provided.

As may be clearly seen in Fig. 3, the upper 105 edge of the carrier is beveled at 21, while the lower edge of the ejector-lug 16 is beveled in the opposite direction at 22. When the carrier is now moved toward the right, the oppositely-beveled faces 21 and 22 will be engaged, and thus lift up the feeler-lever 14 to the position shown in Fig. 1, whereupon the tripping-hook 11 will be returned by the spring 13 to its initial position and again support the outer end of the feeler-lever until 115 such time as the tripping-pin 9 is again caused to act.

What I claim as my invention is—

1. In a type-distributing machine a plurality of sets of type selecting and ejecting devices having all of the tripping-pins of each set of a different size from the tripping-pins of any other set.
2. In a type-distributing machine two sets of type selecting and ejecting devices, one 125 set having tripping-pins which can enter a nick common to all of the types of a font, and the other set having tripping-pins which cannot enter such font-nick.
3. In a type-distributing machine two sets 130

of type selecting and ejecting devices, all of one set having tripping-pins of such size as to enter a nick common to all of the types of a font, and the other set having tripping-pins too large to enter such font-nick.

4. In a type-distributing machine the combination with a pivoted type-ejecting lever, of a type - carrier having a beveled edge adapted to engage with the type-ejecting lever, and means for moving the type-carrier

laterally with reference to said lever thereby lifting the lever to its normal position.

Signed at New York city, in the county of New York and State of New York, this 26th day of June, A. D. 1905.

FRANK McCLINTOCK.
